UNITED STATES PATENT OFFICE

135,136

DESIGN FOR A DISPLAY CARD OR SIMILAR ARTICLE

Morris Aron, South Norwalk, Conn., assignor to
M. Aron Corporation, New York, N. Y., a corporation of New York

Application November 2, 1942, Serial No. 108,675

Term of patent 7 years

To all whom it may concern:

Be it known that I, Morris Aron, a citizen of the United States and a resident of the Town of South Norwalk, Fairfield County, State of Connecticut, have invented a new, original, and ornamental Design for a Display Card or Similar Article, of which the following is a specification, reference being had to the accompanying drawing, forming a part hereof, in which:

Figure 1 is a top plan view of a display card or similar article, showing my new design; and

Fig. 2 is a cross-sectional view, taken on the line 2—2 of Fig. 1.

I claim:

The ornamental design for a display card or similar article, as shown.

MORRIS ARON.
